DESIGN FOR A RADIO CABINET

Edward D. Marsh, Chicago, and Minerva R. Wiffler, Glenview, Ill.

Application July 23, 1938, Serial No. 78,684

Term of patent 7 years

To all whom it may concern:

Be it known that we, Edward D. Marsh and Minerva R. Wiffler, citizens of the United States, residing at Chicago and Glenview, respectively, in the county of Cook and State of Illinois, have invented a new, original, and ornamental Design for Radio Cabinets, of which the following is a specification, reference being had to the accompanying drawing, forming part thereof.

The figure is a perspective view of a radio cabinet showing our new design, the cabinet being substantially the same in appearance at opposite side faces.

We claim:

The ornamental design for a radio cabinet, as shown and described.

EDWARD D. MARSH.
MINERVA R. WIFFLER.
